UNITED STATES PATENT OFFICE.

THOMAS SILLIMAN, OF THREE RIVERS, MICHIGAN.

MECHANICAL MOTOR.

SPECIFICATION forming part of Letters Patent No. 242,798, dated June 14, 1881.

Application filed April 30, 1881. (No model.)

To all whom it may concern:

Be it known that I, THOMAS SILLIMAN, of Three Rivers, in the county of St. Joseph and State of Michigan, have invented certain new 5 and useful Improvements in Mechanical Motors; and I do hereby declare that the following is a full, clear, and exact description of the invention, which will enable others skilled in the art to which it appertains to make and 10 use the same, reference being had to the accompanying drawings, which form a part of this specification.

Figure 1 is a side view of my improved mechanical motor. Fig. 2 is a top view. Fig. 3 15 is a sectional view taken in a vertical plane through the shaft of the escapement-wheel. Fig. 4 is a vertical sectional view longitudinally through the operating-lever; and Fig. 5 is a detail view, in perspective, of the escape- 20 ment and operating mechanism.

Corresponding parts in the several figures are denoted by like letters of reference.

This invention relates to mechanical motors of that class which are run by weights and 25 used for the purpose of operating churns, pumps, and light machinery; and it consists in certain improvements in the escapement, by which the operation of the device is regulated and the rotary converted into a reciprocating 30 motion, as will be hereinafter fully described, and particularly pointed out in the claims.

In the drawings hereto annexed, A represents the frame of the machine, at the end of 35 which is erected a frame tower, B, provided at its top with bearings C for a shaft, D, carrying a pulley, E.

F is the winding-drum, the shaft of which is journaled in the sides of frame A.

G is a gear-wheel journaled loosely upon 40 said shaft, and provided, in the usual manner, with a spring-pawl, H, engaging a ratchet, I, formed upon the winding-drum. A chain or rope, J, attached to the latter, passes over the pulley E, and has a weight, K, attached to its 45 free end. It will be seen that by winding the rope upon the drum by means of a key or crank attached to the shaft of the latter the weight is raised, and when allowed to drop rotates the winding-drum, together with the gear-wheel G, which is connected thereto by the pawl and ratchet. The gear-wheel G engages

a pinion, L, upon a shaft, M, carrying at its outer end the escapement-wheel N. The latter consists of two parallel vertical disks, O O, connected by a suitable number of equidistant 55 cross-pieces, P P.

Q is a lever journaled in a suitable bracket upon the side of the frame, and provided at one end with a pivoted pitman, R, which may be weighted at its lower end. The rod or pitman 60 R has a notch, S, formed in one side, which may engage the cross-pieces P of the escapement-wheel. The outer end of lever Q may be connected by a pitman, T, to the handle of a pump, or in any suitable manner to the machinery to be operated.

U is a lever, pivoted to a bracket, V, upon the outside of the frame by a slot, W, in said lever, which latter is provided with a spring, X, attached to the bracket V, as shown in 70 broken lines in Fig. 1. The upper end of lever U is provided with a notch, Y, engaging the cross-pieces P of the escapement-wheel, as shown.

To the side of the lever U is pivoted a trip-lever, Z, the purpose and operation of which will be hereinafter described.

A guide, A', for the pitman or rod R is secured to the side of the frame, to which a bracket, B', having studs or stops C' for the 80 lever Q, is likewise secured.

To operate the trip-lever Z, a stud, D', secured upon the side of the lever Q, is employed. The said lever Q is also provided with an adjustable weight, E', by placing which at a 85 greater or less distance from the fulcrum the motion may be accelerated or retarded.

A bracket, F', pivoted to the side of frame A, is provided with a crank-handle, G', and with a stud, H', upon which latter the lever Q 90 may be supported when it is desired to temporarily discontinue the operation of the machine.

From the foregoing description, taken in connection with the drawings hereto annexed, the 95 operation of my invention will be readily understood.

When the escapement-wheel revolves one of its cross-pieces will engage the notch in rod or pitman R, thus raising the latter and causing 100 a downward motion or stroke of the outer end of lever Q. The upstroke is caused by the ad-

justable weight E' upon the inner end of said lever. When the rod R has been carried up to the limit of the cross-piece P, which it at the time engages, the said cross-piece catches 5 in the notch Y of lever U, which thus temporarily retains the escapement-wheel in a stationary position, together with the operating-weight and intermediate mechanism. The lower end of the rod R is now brought in contact with the next cross-piece P of the escapement-wheel, which forces it in a rearward direction, thus releasing its upper notched end from the first cross-piece, thus permitting the lever Q to drop, impelled by weight E', until 15 the stud D' strikes the trip-lever Z, thus releasing the lever U from its hold upon the escapement-wheel, permitting the latter to turn and lift the rod R for a repetition of the operation. The spring X at the end of lever U serves to 20 prevent any sudden and injurious shock as the escapement-wheel revolves.

This machine is simple, inexpensive, and very convenient for operating any light machinery. It will be particularly observed that the motion 25 of the escapement-wheel and weight is intermittent, thus giving at each part turn of the said escapement-wheel a fresh impetus, the result of which is to save power, and accordingly increasing the usefulness of the machine.

Having thus described my invention, I claim 30 and desire to secure by Letters Patent of the United States—

1. In a mechanical motor, the combination, with an intermittently-operating escapement-

wheel and weight, of continuously-operating 35 converting mechanism, as and for the purpose set forth.

2. The escapement-wheel herein described, consisting of flat vertical disks connected by equidistant cross-pieces P, as herein described. 40

3. The combination, with the escapement-wheel having cross-pieces P, of the lever Q, having pivoted rod or pitman R, provided with notch S, as and for the purpose set forth.

4. The combination of the escapement-wheel, 45 the lever Q, having pivoted notched rod R, and the adjustable weight E', substantially as described, for the purpose set forth.

5. The combination, with the escapement-wheel having cross-pieces P, of the lever U, 50 having notch Y and trip-lever Z, as and for the purpose set forth.

6. The combination, with the escapement-wheel, of the lever U, having notch Y, trip-lever Z, slot W, and spring X, as and for the 55 purpose set forth.

7. The combination of the escapement-wheel, the lever Q, having pivoted notched rod R and stud D', and the lever U, having notch Y and trip-lever Z, as and for the purpose shown and 60 specified.

In testimony that I claim the foregoing as my own I have hereto affixed my signature in presence of two witnesses.

THOMAS SILLIMAN.
